(57) **CLAIM**

The ornamental design for a folding stool, as shown and described.

DESCRIPTION

FIG. 1 is a front, right and top perspective view of a first embodiment of a folding stool, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2.

FIG. 10 is another front, right and top perspective view of the folding stool in a folded state.

FIG. 11 is a front, right and top perspective view of a second embodiment of a folding stool.

FIG. 12 is a rear, left and bottom perspective view of the second embodiment of the folding stool of FIG. 11.

FIG. 13 is a front elevation view of the second embodiment of the folding stool of FIG. 11.

FIG. 14 is a rear elevation view of the second embodiment of the folding stool of FIG. 11.

FIG. 15 is a left side elevation view of the second embodiment of the folding stool of FIG. 11.

FIG. 16 is a right side elevation view of the second embodiment of the folding stool of FIG. 11.

FIG. 17 is a top plan elevation view of the second embodiment of the folding stool of FIG. 11.

FIG. 18 is a bottom plan elevation view of the second embodiment of the folding stool of FIG. 11.

FIG. 19 is an enlarged view of detail 19 in FIG. 12; and, FIG. 20 is another front, right and top perspective view of the folding stool in a folded state.

The broken lines depict portions of the folding stool that form no part of the claimed design. The dot-dash broken

(Continued)

lines in FIGS. 2, 9, 12, and 19 depict the boundaries of the enlargements that form no part of the claimed design.

1 Claim, 20 Drawing Sheets
